UNITED STATES PATENT OFFICE.

AUGUSTUS T. HATCH, OF SAN FRANCISCO, CALIFORNIA.

DESIGN FOR A BADGE.

SPECIFICATION forming part of Design No. 21,875, dated October 4, 1892.

Application filed July 18, 1892. Serial No. 440,407. Term of patent 3½ years.

To all whom it may concern:

Be it known that I, AUGUSTUS T. HATCH, a citizen of the United States, residing at the city and county of San Francisco, State of California, have invented and produced a new and original ornamental Design for Badges, &c, of which the following is a specification, reference being had to the accompanying drawing, showing a part thereof.

10 The leading feature of my design consists of a bear-head with a globe-like body or sphere representing the world depending therefrom, the head of the bear being mounted upon a shield, which is surrounded by or 15 from which project cornucopias.

Referring to the drawing, the letter A is used to indicate the shield of my design, which has stamped or impressed thereon the head of a bear B, from the mouth of which said 20 bear depends the link chain C, to which is at-

tached the representation of the world, (indicated by the letter D.) From each side of the shield forwardly project or extend cornucopias E E', from the mouths of which are indicated as flowing fruits and flowers, as will 25 be seen by reference to the drawing. The top of shield A terminates in a cross-bar F.

Having thus described my ornamental design, what I claim as new, and desire to secure protection in by Design Letters Patent of the 30 United States, is—

The design for a badge herein described and shown.

In testimony whereof I have affixed my signature in the presence of two witnesses.

AUGUSTUS T. HATCH.

Witnesses:

W. A. ACKER,
J. C. MCKEE.
